UNITED STATES PATENT OFFICE.

LEE S. CHADWICK, OF EAST CLEVELAND, OHIO.

STOVE.

1,122,857.

Specification of Letters Patent. Patented Dec. 29, 1914.

Original application filed October 25, 1913, Serial No. 797,217. Divided and this application filed July 23, 1914. Serial No. 852,612.

To all whom it may concern:

Be it known that I, LEE S. CHADWICK, a citizen of the United States, residing at East Cleveland, in the county of Cuyahoga and State of Ohio, have invented a certain new and useful Improvement in Stoves, of which the following is a full, clear, and exact description, reference being had to the accompanying drawings.

10 This invention relates to stoves, and more particularly to stoves of the type employed with liquid or gaseous fuel.

It is the general object of the invention to provide a stove of this character which 15 is not only simple and economical of production but slighty and attractive in appearance.

It is a further object of the invention to produce a stove which may be constructed 20 principally of sheet metal, but which will be capable of withstanding the incidents of use while retaining the other advantages referred to hereinbefore.

The invention disclosed herein is taken 25 from my application No. 797,217, filed Oct. 25, 1913, of which this application is a division.

In the drawings forming part hereof, Figure 1 is a front elevation, and Fig. 2 30 an end elevation, of a stove constructed in accordance with my invention; Fig. 3 a vertical sectional view, the section being taken on a plane passing near the front of the stove; Fig. 4 a horizontal sectional view 35 through the lower portion of the stove 1, above the supply pipe; and Fig. 5 a detail in perspective of one of the corners of the stove base.

Describing by reference characters the 40 various parts illustrated herein, 1 denotes a downwardly and outwardly flaring skirt which depends from a rectangular base plate 2, the upper end of the skirt projecting above the plane of the plate and forming 45 therewith an upwardly projecting peripheral bead 3. The lower end of the skirt is bent inwardly to form a "false wire," as shown at 4. Each corner of the skirt is cut out, as shown at 5 (see Fig. 5) the recess thus formed extending from the bottom of the skirt upwardly approximately as far as the top of the bead 3.

The base (comprising the plate 2 and skirt 1) may be supported by legs, indicated 55 generally at 6. These legs are preferably

of sheet metal and comprise each an angular flange 7, which is adapted to fit beneath the skirt 1, the flanges being of sufficient length to extend beyond the recesses 5 and being of such shape as to conform to the under surface of the skirt 1 on each side 60 of such recess. The legs are perfectly made of sheet metal and are conveniently held in place by means of angular plates 8 (preferably of sheet metal) and of sufficient extent 65 to cover the recesses 5 and extend beyond the lateral edges thereof and of such shape as to conform to the outer surface of the skirt 1 on each side of said recess. These plates cover the recesses 5 and in effect, complete 70 and form the corners of the skirt, being of such shape and size as to fit the portions of the skirt on each side of each recess 5. The said plates form means whereby the legs may be secured in place, stove bolts 9 being 75 used for the purpose of connecting the legs and the plates to the skirt.

The space above the base plate 2 and below the stove top plate and the oven, is divided into a plurality of compartments A, 80 B, and C. The compartment A is shown as open at the back and is located below the oven D and contains the oil distributing receptacle and the oil dispensing receptacle; the compartment B is shown as open at the 85 front and closed at the back, is adjacent to the compartment A and located beneath the oven D and is provided with a burner for operating the oven thereabove. The compartment C is also shown as open at the 90 front and closed at the back. It contains the cooking burners and is located below the stove top. The particular construction whereby the various compartments are produced will now be described. 95

A pair of end panels project upwardly from opposite ends of the base plate, each panel fitting within the bead 3. The right hand end panel is shown as provided with inwardly projecting top and bottom flanges 10. Each vertical edge of this panel and one of the vertical edges of the left hand panel are provided with tubular columns 11, the metal being bent in such a way as to provide columns which are elliptical in 105 section, the columns being open toward the interior of their respective compartments. The front lateral edge of the left hand panel is provided with a bead 12, which may be formed by bending or curving the plate out 110

wardly toward the end of the stove and then back for a short distance parallel to the long side of the base. This bead fits within a similarly shaped bead or column 13 formed at the left hand end of a front plate 14, which front plate covers the front of the compartment A. This plate is provided with a door opening, the metal surrounding the opening being flanged inwardly, as shown at 14^a. Each end panel is provided with an outwardly projected rectangular central portion 15 bounded by an outwardly projecting bead 16 and connected to the peripheral portion of the panel 15 by inclined surfaces 17. This construction strengthens the panels (which are preferably of light sheet metal) and contributes to the ornamental appearance of the same. The left hand panel is provided with a bottom flange 10, similar to the like designated flange on the right hand panel. At its upper end however, the left hand panel as connected by stove bolts 18 with an angle flange 19 depending from the oven 20. The bottom flanges 10 are connected to the stove base, as by means of stove bolts 21, and the similarly designated top flange of the right hand panel is connected in like manner to the stove top 22, which is located above the burners 23 (employed for ordinary cooking purposes) and which is provided with openings for the grids 24 located above said burners. The top 22 is provided with a depending flange 22^a extending therearound, and the openings above the burners are conveniently reinforced by bending down the metal, as indicated at 24^a, to form annular flanges.

25 denote a back plate the bottom whereof 40 is supported from the base 2 by means of a flange 26 and stove bolts 27, the upper end of the plate assisting to support the top plate 22 and being connected to said plate in any convenient manner. The ends of the 45 plate 25 are bent inwardly to form flanges, as shown at 28, the right hand flange coöperating with the right hand end panel and the left hand edge coöperating with a vertical partition 29, which extends substantially 50 parallel with the panels, is provided with a flange 30 by means of which it is secured to the base 2 (as by stove bolts) and is secured at its upper end to an angle flange 31 projecting downwardly from the oven 20. The 55 front and back edges of the plate 29 are bent to give a tubular or hollow-column effect, as indicated at 31, this effect being produced in the same manner and the resultant appearance being the same as in the case of the tubular or hollow columns 11.

60 32 denotes a partition which extends parallel with the partition 29 and is located between the same and the left hand panel of the stove. This partition 32 is provided 65 with flanges 33 and 34 at the top and bot-

tom thereof by means of which, respectively, it may be secured to the base plate 2 and the bottom of the oven 20. The partition 32 is preferably formed integral with the front plate 14, the two plates forming together an angle plate. 35 denotes the back plate, which coöperates with the plates or partitions 29 and 32 to form a compartment for the oven heating burner 39. The plate 35 may be conveniently retained in place by means of the flange 36 at the bottom thereof, which may be bolted to the base plate 2, and by means of lateral flanges 37 and 38 coöperating respectively with the partitions 32 and 29, the upper end of the plate 35 abutting against and being secured to the bottom of the oven.

From the bottom of the distributing receptacle there projects an oil supply pipe 40, said pipe extending through the partitions 32 and 29 and the right hand panel of the stove, the right hand end of the pipe being closed by a suitable cap 41. The pipe may be supported by means of a plate 42 carried by the partition 29 and to which the pipe is secured by means of a clamp 43 (shown in detail in my application No. 797,217 hereinbefore referred to; also by means of a bracket 44 which projects upwardly from the plate 2).

The left hand end of the pipe 40 projects downwardly from and communicates with the bottom of a cylindrical cup 45, forming the distributing receptacle, there being a rectangular drain sink 46 having an inclined bottom 47 extending below the top of the cup 45 and communicating with said cup. The receptacle 37 is mounted in a carrier 48 which is carried by a door pivoted to the front of the compartment included between the partition 32 and the left hand panel. The details of construction whereby the receptacle is supported and swung into and out of place within its compartment form the subject matter of a divisional application.

105 The oven 20 is described at length in my application No. 797,217, with the exception of a detail which will appear hereinafter. As illustrated herein and in said application, the oven comprises generally a pair of walls 49 and 50 having lagging 51 therebetween, the lagging surrounding the top, sides and rear of the oven. Within the oven space proper is a lining 52 having openings 53 in the top thereof communicating with down flues 54 which communicate at their bottom, through passageways 55, with vertically extending flues 56. At their upper ends, the flues 56 communicate with a flue 57 covering the top of the oven and the lagged space between the plates 49 and 50. In the oven shown herein, the flue 57 is provided with a sheet of corrugated metal 58, which spaces the walls 49 and 59 thereof apart. 130

After passing through the flue 57, the products of combustion from the burner 39 pass through the collar 60 into a suitable outlet pipe (not shown).

5 The back wall of the oven is preferably formed in part by the back plate 61, which extends the full length of the stove and some distance above the top of the oven. An end plate 62, supported on top of the plate 22, 10 extends from the rear portion of the right hand end of the stove top 22 to a height substantially equal to that of the oven, and the upper edge of this plate and the top of the oven are shown as connected by a warming 15 shelf 63. That portion of the back plate 61 which extends above the shelf 63 and above the top of the oven may be supported by means of a pair of angular brackets 64. The forward edges of the warming shelf and of 20 the end piece 62, as well as the upper edge of the back plate 61, may be stiffened and artistically finished by means of metallic binding 65.

By the construction illustrated and described herein, it will be apparent that I have produced a stove base which, while very economical of production, possesses all of the rigidity of one wherein the depending flange 19 is continuous, such rigidity being secured in and through the coöperating construction of the legs and the clamping plates 9. It will be evident further that I have produced a coöperating construction of stove base, side and end walls and stove top where 35 by the burners and the oil reservoir are inclosed and protected and this result is secured in and through the use of relatively inexpensive light sheet metal, the parts being connected and shaped in such manner as 40 to produce an efficient and attractive construction.

For convenience of distinguishing the transverse partitions one from the other, I have employed the term "panel" in connection with the rectangular plates at the ends of the stove base and have referred to the intermediate plates 29 and 32 as "partitions." As the parts referred to are made from plates of sheet metal, the term "plate" 50 will be used as the term to designate these parts generically.

Having thus described my invention, what I claim is:—

1. In a stove of the character described, 55 the combination of a base, rectangular end panels mounted on the base and having tubular vertical edges, a back plate interposed between the rear edges of said panels, a top supported by and above the panels and the back plate, and one or more burners located between said base and the top.

2. In a stove of the character described, 60 the combination of a base, rectangular plates mounted on the base and having tubular vertical edges, a top supported by and above

the plates, and one or more burners located between said base and the top.

3. In a stove of the character described, 70 the combination of a rectangular base having an upwardly projecting peripheral bead, a plurality of plates mounted within the bead and projecting thereabove, a top supported by said plates and forming a compartment therewith and with the base, and one or more burners in said compartment. 75

4. In a stove of the character described, 80 the combination of a sheet metal base of rectangular form having an upwardly projecting peripheral bead and a skirt depending from said bead, a pair of plates supported by said base and mounted within the bead, a back plate interposed between the plates and projecting upwardly from the base and located within the bead, a stove 85 top mounted above said plates and having one or more openings therein, and a burner or burners located below said opening or openings and between the top plate and the base. 90

5. In a stove of the character described, 95 the combination of a sheet metal base of rectangular form having an upwardly projecting peripheral bead and a skirt depending from said bead, a pair of end panels supported by said base and mounted within the bead, a back plate interposed between the end panels and projecting upwardly from the base and located within the bead, a stove top mounted above said panels and 100 having one or more openings therein, and a burner or burners located below said opening or openings and between the top plate and the base.

6. In a stove of the character described, 105 the combination of a rectangular base, end panels mounted on said base and projecting upwardly therefrom, a pair of transverse partitions also mounted on said base and interposed between said panels, back plates 110 mounted on the base and forming with one of the end panels and the two partitions a pair of compartments, one or more burners in the compartment formed between the end panel and the partition adjacent thereto, 115 a burner in the compartment formed between said transverse partitions, a stove top covering the first mentioned compartment and having one or more burner openings therein, an oven mounted above the other compartment, and a reservoir in the space between the oven burner compartment and the remaining end panel. 120

7. In a stove of the character described, 125 the combination of a rectangular base, end panels mounted on said base bead and projecting upwardly therefrom, a pair of transverse partitions also mounted on said base and interposed between said panels, back plates mounted on the base and form- 130

ing with one of the end panels and the partitions a pair of compartments, one or more burners in the compartment formed between the end panel and the partition adjacent thereto, a burner in the compartment formed between said partitions, a stove top covering the first mentioned compartment and having one or more burner openings therein, an oven mounted above the other compartment and covering the space between the remaining end panel and the adjacent partition, a front plate extending across the space between said panel and partition, and an oil distributing receptacle in the compartment thus formed.

8. In a stove of the character described, the combination of a base, end, intermediate and back plates mounted on the base and projecting upwardly therefrom, means extending across the tops of said plates and providing a plurality of compartments with said plates and the base, a fuel receptacle in one of said compartments, and burners in the remaining compartments.

9. In a stove of the character described, the combination of a base, end, intermediate and back plates mounted on the base and projecting upwardly therefrom, means extending across the tops of said plates and providing a plurality of open-front compartments therewith, a front plate mounted on said base and extending between two of said plates and forming a compartment therewith, a fuel receptacle in the last mentioned compartment, and burners in the first-mentioned compartments.

10. In a stove of the character described, the combination of a base plate, end panels mounted on said base plate and projecting upwardly therefrom, a pair of transverse partitions mounted on said base and projecting upwardly therefrom, a back plate extending from one of the end panels to the transverse partition adjacent thereto, a second back plate extending between the transverse partitions and connecting the same, a top plate covering the space between the first mentioned end panel and the transverse partition adjacent thereto, an oven covering the space between said transverse partition and the other end panel, an oven heating burner in the space between the transverse partitions, one or more burners in the first mentioned space, and an oil receptacle for said burners located in the space between the second transverse partition and the adjacent end panel.

11. In a stove of the character described, the combination of a base plate, a plurality of transverse plates mounted upon and projecting upwardly from said base plate, each transverse plate having its front edge bent into the form of a tubular column, and burners interposed between said plates.

12. In a stove of the character described,

the combination of a base plate, a pair of transverse plates mounted on said base plate and having their front and rear edges formed into tubular columns, a back plate interposed between said transverse plates and in front of the tubular columns at the rear edges thereof, and one or more burners interposed between said transverse plates.

13. In a stove of the character described, the combination of a base plate, a pair of transverse plates mounted on said base plate and having their front and rear edges formed into tubular columns, a back plate interposed between said transverse plates and in front of the tubular columns at the rear edges thereof, a top plate above said plates, and one or more burners in the compartment thus formed.

14. In a stove of the character described, the combination of a base plate, a pair of end panels carried by the base plate and projecting upwardly therefrom, each of said panels having its front edge formed into a tubular column, a combined front wall and partition interposed between said panels and forming a tank receiving chamber with the adjacent end panel, said combined front wall and partition having an opening in the front thereof for the insertion of a receptacle and being provided with a tubular portion conforming to and receiving therewithin the tubular front edge of the co-operating end panel.

15. In a stove of the character described, the combination of a base plate, an end panel carried by the base plate and projecting upwardly therefrom, said panel having its front edge formed into a tubular column, a combined front wall and partition forming a tank receiving chamber with said end panel, said combined front wall and partition having an opening in the front thereof for the insertion of a receptacle and being provided with a tubular portion conforming to and receiving therewithin the tubular front edge of the said panel.

16. In a stove of the character described, the combination of a base plate, a pair of end panels projecting upwardly therefrom, a transverse partition interposed between said panels and adjacent to one of the same, a front plate uniting said partition and the adjacent end panel and having an opening therein for the insertion of a liquid fuel receptacle, one or more burners interposed between the partition and the other end panel, and a supply pipe extending between the receptacle and said burner or burners.

17. In a stove of the character described, the combination of a base plate, a panel at each end of said base plate and each having a flange at its bottom, means securing said flanges to the base plate, a transverse partition interposed between said panels, an oven mounted above the space between said par-

tion and one of the end panels, angle clips connecting the upper end of said partition and the upper end of the last mentioned panel to the bottom of the oven, a burner 5 below the oven and in the space between the partition and the said panel, and a back plate projecting upwardly from the base plate and interposed between the partition and the other end panel and extending upward to the oven.

18. In a stove of the character described, the combination of a base plate, an end panel projecting upwardly therefrom, a partition mounted adjacent to the panel and 15 projecting upwardly from and secured to the base, a second partition interposed between the first mentioned partition and the second transverse partition and secured to the base plate, a back plate mounted on the 20 base plate and closing the back of the space formed between said partitions, an oven

mounted above said partitions, back plate and one of said panels and covering the spaces therebetween, a burner in the space between said partitions, and an oil supply 25 reservoir in the other space below the oven and communicating with said burner.

19. In a stove of the character set forth, the combination of a substantially rectangular base having a peripheral bead and a skirt depending from the outer edge thereof, plates extending upwardly from said base from within said bead, a top supported by said plates and one or more burners located between the base and the top.

30 In testimony whereof, I hereunto affix my signature in the presence of two witnesses.
